(57) **CLAIM**

The ornamental design for a ballast for a work vehicle, as shown and described.

DESCRIPTION

FIG. 1 is a rear perspective view of a ballast for a work vehicle according to an exemplary embodiment of the present subject matter.

FIG. 2 is a rear view of the ballast illustrated in FIG. 1.

FIG. 3 is a front view of the ballast illustrated in FIG. 1.

FIG. 4 is a first side view of the ballast illustrated in FIG. 1.

FIG. 5 is a second side view of the ballast illustrated in FIG. 1.

FIG. 6 is a top view of the ballast illustrated in FIG. 1.

FIG. 7 is a bottom view of the ballast illustrated in FIG. 1; and,

FIG. 8 is another rear perspective view of the ballast illustrated in FIG. 1, particularly illustrating an environmental view of the ballast installed on a work vehicle, such as a wheel loader.

The broken lines contained within the figures, including, but, not limited to, any dash-dot broken lines and/or dash-dash broken lines, represent portions of the ballast for a work vehicle that form no part of the claimed design. Additionally, contour lines and/or surface shading are illustrated simply for purposes of highlighting the solid-rendering, and, thus, form no part of the claimed design.
